(57) **CLAIM**

The ornamental design for a solar panel assembly, as shown and described.

DESCRIPTION

FIG. 1 is a top, front, and right perspective view of a solar panel assembly in a retracted position, showing my new design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof;

FIG. 8 is a top, front, and right perspective view of the solar panel assembly of FIG. 1 in the retracted position mounted on a vehicle;

FIG. 9 is a top, front, and right perspective view of a solar panel assembly in an extended position, showing my new design;

FIG. 10 is a right side view thereof;

FIG. 11 is a left side view thereof;

FIG. 12 is a front view thereof;

FIG. 13 is a rear view thereof;

FIG. 14 is a top view thereof;

FIG. 15 is a bottom view thereof; and,

FIG. 16 is a top, front, and right perspective view of the solar panel assembly of FIG. 9 in the extended position mounted on a vehicle.

The even length broken lines in the drawings depict environmental subject matter that forms no part of the claimed design.
